GUN TRUNNION

Hubert F. Franklin, Baldwin, N. Y., assignor to
 Republic Aviation Corporation, a corporation
 of Delaware

Application November 10, 1943, Serial No. 509,717

6 Claims. (Cl. 89—37.5)

1

This invention relates to gun trunnions or mounts, of the universal type, and contemplates a device of this character having independent adjustments for the horizontal and the vertical planes, in which the gun, such as a machine gun may be quickly and readily mounted and from which it may be as quickly and as readily detached, all without affecting the adjustments of the trunnion or mount but permitting any necessary or desirable adjustments while the gun is supported by the trunnion.

With the above and other objects in view, as will be apparent, the invention consists in the construction, combination and arrangement of parts, all as hereinafter more fully described, claimed and illustrated in the accompanying drawings, wherein—

Fig. 1 is a plan view of a gun mount or trunnion constructed in accordance with the present invention:

Fig. 2 is a transverse section along line 2—2 of Fig. 1 illustrating the mount in elevation and a part of its support in section:

Fig. 3 is a transverse section along line 3—3 of Fig. 1:

Fig. 4 is an end elevation of the trunnion or mount:

Fig. 5 is a vertical section along line 5—5 of Fig. 3; and

Fig. 6 is a fragmentary section similar to Fig. 3 illustrating a modified form of this invention.

As is well known, a machine gun, especially when mounted in the wing of an aircraft, has a double support, viz., an adjustable rear mount cooperating with its butt end assembly and a trunnion structure spaced from the rear gun mount forwardly of the gun barrel or jacket and cooperating with the barrel or jacket at some point between the butt end assembly and the muzzle of the gun. As the rear gun mount, which forms no part of the present invention, is usually adjustable in both the vertical (elevation) and the horizontal (azimuth) planes for aiming purposes, the trunnion structure, forming the subject of the present invention and cooperating with the rear mount for the support of the gun, is movable about axes lying in these planes with the aiming movements of the rear gun mount. At the same time the instant invention incorporates means for relatively small independent adjustments of the trunnion structure in both the vertical and the horizontal planes to permit of a true centering of the gun and an accurate initial aiming adjustment in either or both of these planes, which adjustments once

5 having been made become fixed or permanent. This trunnion or mount structure also provides for these several adjustments to be effected while the gun is engaged within or by the trunnion structure and at the same time provides for the quick mounting and detachment of the gun without disturbing any of the adjustments of the trunnion structure or of its parts.

Reference being had more particularly to the 10 drawings, 10 designates a supporting structure such as the transverse ribs of an aircraft wing structure, upon which and to which the trunnion or mount forming the subject matter of the present invention secures a machine gun. In the 15 drawings, 11 designates the barrel of the gun, and 12 the jacket therefor. The jacket 12 of the gun is encircled and fixedly engaged by an adapter 13 having the conical journals 14 at the ends of its vertical diameter.

20 The gun mount or trunnion which is to receive and cooperate with an adapter 13 secured to a machine gun comprises a lower jaw 15 and an upper jaw 16. The lower jaw 15 is shaped to conform generally to the contour of the jacket 12 and the adapter 13 and is mounted between the ribs 10 for pivotal movement about a horizontal axis to permit of the elevational aiming adjustment of the gun. That is accomplished by providing a supporting bearing 17 at each end 25 of the lower jaw 15, each of which is pivotally and adjustably secured to one of the ribs 10 as hereinafter more fully described. One of the supporting bearings 17 of the lower jaw 15 is provided on its upper side with a lug 18 to be received between a pair of ears 19 at the corresponding end of the upper jaw 16. The lug 18 and the ears 19 are pivotally secured together by a bolt 20. In this manner the upper jaw 16 is hinged to the lower jaw 15.

40 That end of the upper jaw 16 opposed to the hinge comprising the ears 19, lug 18 and bolt 20 is provided with a substantially horizontal projection 21 having a longitudinal groove 22 in the outer face thereof. This projection 21 extends over and lies substantially parallel to the inner end of the adjacent supporting bearing 17. To secure the free or unhinged end of the upper jaw 16 to the lower jaw 15, a yoke 23, provided with the arms 23', spans the jaws 15—16 with its arms on opposed sides of the jaws and pivoted as at 24 at their terminals to the lower jaw below and in approximate alignment with the inner end of the adjacent supporting bearing 17. Medially of their length the arms 23' of the yoke are bent inwardly, as at 23'', toward the approximate

vertical center of the bearing, and this bend occurs at or near the horizontal projection 21 of the upper jaw 16.

A lock operating rod 25 is threaded through the yoke 23 medially of its length between the arms 23' thereof and in order to provide a substantial mounting for this rod 25 a sleeve 26 is secured to the inner face of the yoke 23 in alignment with the passage through which the rod 25 is threaded. The interior of this sleeve 26 is threaded in continuation of the threads of the opening in the yoke through which the rod 25 passes and since the sleeve 26 in effect constitutes a unitary piece with the yoke 23, having a threaded passage through these elements for co-operation with the threads of the rod 25, an elongated threaded bearing is provided for the rod 25. A shell 27 encircles the rod 25 and is provided with a series of locking depressions 28 in its outer end wall which cooperate with a wing nut 29 fixed to the rod 25. A compressed coil spring 30 is interposed between the end wall of the shell and the yoke 23 to constantly force the shell upwardly into contact with the inner edge of a wing nut 29 fixedly secured to the projecting end of the rod 25, whereby the wing nut is seated in one or the other of the depressions 28 and is held thereby from any tendency to rotate relatively to the shell or to the yoke. To prevent the shell 27 from rotating with respect to the rod 25 and the yoke 23, it is provided with a pair of extensions 31, one upon each side of the yoke 23, spaced one from the other to provide a space for the reception of the yoke. These extensions 31 at all times contact with the edges of the yoke 23 regardless of the position of the shell 27 and prevent any rotary movement of the latter relative to either the yoke 23 or to the rod 25.

To brace the sleeve 26, as well as the arms 23' of the yoke 23, a pair of plates 32 are interposed between the arms 23' adjacent to their junction with the cross member of the yoke 23 and these plates 32 rest flush one against the other except where they are each bent outwardly, as at 33, to embrace the sleeve 26. The plates 32 may be welded or otherwise permanently secured to the cross member of the yoke 23, to the arms 23' thereof and to each other and at their centers, where they cooperate with the sleeve 26, separate, as at 33, to combine in creating a passage in which and through which the sleeve 26 extends and passes.

At its inner end the adjusting rod 25 is connected to a pin 34 by means of a swiveled connection 35. As the rod 25 rotates it, of course, travels through the yoke 23 and the aligned sleeve 26 and is adjusted with respect to these elements. By reason of the swivel or loose rotary connection 35 between the inner end of this rod and the pin 34, this pin moves with the rod along the axis of the rod but does not rotate with it. Once the rod 25 has attained the desired adjusted position with respect to the yoke 23, the wing nut 29, by which the rod is rotated and adjusted, automatically becomes seated in the radiating recesses 28 in the outer wall of the shell 27 thereby locking the rod from further rotation.

Just above the bends 23'' in the arms 23' of the yoke 23 and in a plane approximating the plane of the projection 21 of the upper jaw 16, each arm 23' is provided with a slot 36, the slot 36 of one arm being aligned transversely of the yoke with the slot 36 of the opposite arm. A lock bar 37 having the ears 38 at its ends is reciprocatingly mounted between the arms 23' of the

yoke by means of the ears 38 being slidably received in the slots 36. Medially of this length this lock bar is connected or fixed to the pin 34 so that as the pin is moved towards and away from the projecting portion 21 of the movable jaw 16 under the influence of the wing nut 29, the lock bar 37 similarly moves. On its under surface and extending longitudinally of its length, the lock bar has a rib 39 to be seated in the groove 22 in the horizontal projection 21 of the upper jaw 16 when the lock bar 37 has reached the lower end of its permissible path of movement. Since the jaws 16 and 17 are of relatively soft metal it is undesirable to concentrate any great pressure at a single point. Therefore the bar 37 acts to distribute the clamping pressure between the jaw and prevents any concentration thereof.

From the foregoing it is apparent that the lower or stationary jaw 15, once its ultimate adjustment in a horizontal plane has been attained, occupies a constant position with reference to the ribs 10 by and between which it is supported in a manner to be hereinafter described. Since the yoke 23 is pivoted to one end of the lower or stationary jaw 15 and the upper movable jaw 16 is pivoted to the opposite end of the lower jaw, the jaws may be closed or opened by swinging the jaw 16 to and away from the jaw 15, and when closed the yoke 23 may be positioned as in Fig. 2 to lock the jaw 16 to the jaw 15 outwardly with respect thereto. When the jaws are relatively positioned as shown in the drawings the projection 21 of the upper movable jaw 16 is over and above the corresponding portion of the fixed or lower jaw 15, whereupon the yoke 23 may be swung to a substantially vertical position with the lock bar 37 above the projection 21. The rotation of the wing nut 29 will then cause the rod 25 and pin 34 to move downwardly in the sleeve 26 to bring the lock bar 37 into contact with the projection 21 and seat the rib 39 in the groove 22 thereof. The continued rotation of the rod in the same direction will cause a pressure to be exerted upon the free end of the upper jaw 16 and will lock it to the corresponding end of the lower jaw 15. It is to be observed that a space remains between the free end of the jaw 16 and the stationary jaw 15 when the jaws are in closed or locking position. As it is the function of the present device to support a gun for movement in two planes and yet do this without undue friction and any play, the provision of this space permits of a range of adjustment of pressure at all times to accomplish this end. The rib 39 of the lock bar 37 seated in the groove 22 of the projection 21 effectively overcomes any tendency of the yoke to swing about its pivot and away from locking engagement with the projection 21 of the upper movable jaw 16. Also the cooperation between the wing nut 29 and the radial depressions 28 in the end wall of the shell 27 will prevent any unintentional retrograde movement of the wing nut and consequently of the rod and lock bar 37. If it is desired to elevate the movable jaw 16 or to move it from the position shown in the drawings to swing it about the pivot 24 thereby opening the jaws, the wing nut 29 may be reversely rotated which will elevate the lock bar 37, remove the pressure on the projection 21 and the rib 39 from the seat 22. This permits the yoke 23 to be swung about its pivot 24 away from the coacting jaws thereby releasing the projection 21 and permitting the upper jaw to be shifted about its pivot 20.

For cooperation with the conical journals 14 formed or mounted on the adapter 13 a pair of bearings 40 is provided, one bearing being centrally positioned in the upper jaw 16 and the other similarly situated in the lower fixed jaw 15, said bearings being aligned vertically of the trunnion structure. Each of these bearings 40 is threaded into its cooperating jaw 15 or 16 and is held in its adjusted position by a nut 41 and a washer 42. The outer end of each bearing 40 is provided with one or more recesses 43 for the reception of a wrench by which the position of the bearing with reference to its jaw may be determined.

The inner end of each bearing 40 is provided with a conical seat 40' for the reception of the conical journals 14 formed on the adapter 13. This structure provides a mount for the gun movable about a vertical axis, and the adjustments provided for the bearings 40 permit of the adjustment of the gun and adapter in a vertical plane. The cooperation of the conical journals 14 with the conical seats 40' of the bearings 40 manifestly centers the gun in a horizontal plane with respect to the mount or trunnion structure as a whole. In short, the cooperation between the journals 14 and the bearings 40, together with the adjustment of the latter, not only centers the gun 12 carried by the adapter 13 with respect to the bearings but also permits the gun to swing in a horizontal plane. By adjusting the bearings 40, the gun as a whole, together with its adapter 13, may be adjusted in a vertical plane between the jaws 15 and 16 of the mounting.

To support the mount between the ribs 10 of the wing structure (not shown) a plate 44 is secured to each rib 10 and each plate carries a hollow horizontal journal 45 in the form of a truncated cone. These plates 44 may be mounted against either face of the supporting ribs 10, one of them preferably being positioned against the face of its coacting rib 10 disposed away from the jaws 15-16 and to that end an aperture must be provided in the rib through which the journal 45 passes. The plates 44 are secured to the ribs 10 by a series of bolts 46.

As above pointed out, each end of the stationary or lower jaw 15 is provided with an outstanding cylindrical supporting bearing 17 aligned one with the other. These bearings project towards and receive the journals 45. In order to adjust the entire bearing in a horizontal plane between the journals 45, there is interposed between the supporting bearings 17 and the conical journals 45 an adjusting mechanism. This mechanism for each bearing 17 comprises an interiorly threaded bushing 47 inserted in each supporting bearing 17 and coextensive therewith. This bushing has a tight friction fit or is otherwise fixedly secured within its bearing 17 so that there is no relative movement between the supporting bearings 17 and the interiorly threaded bushings 47. An auxiliary bearing member 48 is threaded into the bushing 47 and is provided with a conical seat 49 which receives and rides upon the cooperating conical journal 45.

It will be observed that the auxiliary bearing 48 is longitudinally split, as at 50, permitting a compression thereof within the threaded bushing 47 and on the coating journal 45 thereby varying its diameter within relatively small limits so that it may snugly engage the conical surface of the journal 45 at any point. The auxiliary bearing is adjustable within and removable

from the bushing 47 by a wrench engaging the inner end of the auxiliary bearing through the medium of the recesses 51 provided for that purpose. The inner end wall 45' of the journal 45 is provided with a splined aperture in which a splined boss 52 of the nut 53 is received. A bolt 54 having the head 55 passes through a washer 56, and wall 45' and projects into the journal 45 where it is engaged by the nut 53. As the washer 56 bears against the shoulder at the inner end of the conical seat 49 of the auxiliary bearing 48 and as the nut 53 cannot rotate by reason of its fixed splined connection with the inner end wall 45' of the journal 45, and since the journal 45 is immovable, the rotation of the head 55 of the bolt forces the conical seat 49 of the auxiliary bearing 48 outwardly on the conical journal 45. In this manner the conical seat 49 of the auxiliary bearing 48 is adjusted to snugly engage the conical surface of the journal 45 and any looseness or play therebetween is eliminated. Furthermore, the engagement of the washer 56 with the shoulder at the inner end of the conical seat 49 of auxiliary bearing 48 prevents any axial movement between the journal 45 and the auxiliary bearing 48.

To move or adjust the mount in a horizontal plane, the bolts 54 are loosened, thus freeing the washers 56 from engagement with the auxiliary bearings 48. The auxiliary bearings 48 are then rotated the same amount and in the same direction in their respective threaded bushings 47 until the desired horizontal movement has been accomplished. To secure the mount in this position, the bolts 54 are retightened until the washers 56 reengage the shoulders on the inner end of the conical seats 49 of the auxiliary bearings 48 and the conical seats 49 of the auxiliary bearings 48 are snugly engaged with the conical surfaces of the journals 45.

It is to be understood that the adjustments required to properly center the gun with respect to the bearing, the ribs 10 and the leading edge of the wing structure through which it operates are relatively small, so that any large movement of the bearings 40 and/or of the auxiliary bearings 48 is unnecessary. However, by adjusting the bearings 40, threading one outwardly of its jaw, and threading the other inwardly of its jaw the entire gun and adapter 13 may be adjusted in a vertical plane with respect to the jaws. Once these adjustments have been attained so that the gun is initially sighted and properly centered, they become fixed and the upper hinged jaw 16 may be released as above described and the gun removed therefrom, or the gun may be returned to its mounting and engaged between the jaws 15 and 16 without affecting these adjustments in the horizontal and vertical planes.

In Fig. 6 is illustrated a modification of the mechanism by which the free end of the hinged or upper jaw 16 is attached to one of the supported bearings 17. The projection 21 at the end of the jaw 16 is, in this form of the invention, engaged by a ring 57 which has an internal flange 58 threaded for engagement with the external threads 59 on the exterior of the adjacent supporting bearing 17. The rotation of the locking ring 57 for travel inwardly causes the lip 60 thereof to engage over the upper surface of the projection 21 of the jaw 16, and since this upper surface is sloping and the cooperating surface of the lip 60 is similarly formed, there is a cam action which forces the free upper end of the jaw downwardly into clamping position. By re-

versing the rotation of the ring 57 the projection 24 of the upper or hinged jaw 16 is released and the jaw is then free to swing about its hinge 20.

In both forms of the invention the free end of the jaw 16 is provided with a central opening 61 flanked by the projections 62, the inner faces of which incline upwardly and inwardly. These inner surfaces contact with the upper portion of the adjoining supporting bearing 17 upon each side thereof, thereby creating a cam action between the free end of the jaw 16 and the bearing 17 whereby any irregularities in the pivot of the jaw 16, which might otherwise throw the jaw out of perfect alignment with the bearings 17 and with the lower fixed jaw 15, are overcome and a perfect alignment and contact is obtained.

From the foregoing it is manifest that the present trunnion structure enables the gun to be adjusted by the manipulation of the rear gun mount for aiming purposes by providing for its oscillation about the vertical axis represented by the journals 14 and coacting bearings 40 and about the horizontal axis represented by the bearings 17 and 48 and the journals 45. Furthermore the adjustment of the trunnion structure as a whole in the horizontal plane by adjusting the bearings 17 and 48 on the journals 45 and the adjustment of the adapter in the vertical plane by the adjustment of the bearings 40 relative to the jaws 15 and 16, makes possible an initial centering of the gun within the trunnion structure which when once attained remains unchanged regardless of the removal of the gun or of its return to the trunnion.

What is claimed is:

1. The combination with a pair of conical trunnions, of a primary jaw, opposed supporting bearings on said jaw for the reception of said trunnions, an auxiliary bearing adjustably mounted in each supporting bearing and provided with a conical surface for pivotal cooperation with the engaged trunnion, a connection between each trunnion and its coacting auxiliary bearing to adjust the position of the auxiliary bearing in its supporting bearing and with respect to the cooperating trunnion, a secondary jaw hinged to one end of said primary jaw, fastening means carried by the primary jaw for releasably securing the free end of the secondary jaw thereto, opposed bearings carried by the secondary and primary jaws and adjustable with respect thereto, and an adapter to be positioned between said jaws and having journals to be pivotally engaged in said adjustable bearings.

2. The combination with an annular adapter having diametrically opposed journals, of a primary jaw, opposed supporting bearings at the ends of said jaw, fixed trunnions mounted to be received in said supporting bearings, auxiliary bearings interposed between said supporting bearings and said trunnions, adjustable connections between said trunnions and said auxiliary bearings whereby the position of the latter may be adjusted with respect to the former, a secondary jaw hinged at one end to said primary jaw, an engaging member carried by said primary jaw to releasably engage the other or free end of the secondary jaw, and opposed bearings, one attached to each of said jaws, for the reception of the journals on said adapter and adjustable relative to said jaws to position said adapter between said jaws.

3. The combination with a generally-circular gun adapter having diametrically-opposed journals, of a mount providing universal movement

for said adapter, said mount comprising a primary jaw and a movable secondary jaw arranged for opening and closing with respect to the primary jaw, said jaws having their opposed faces disposed in spaced-apart relation to provide a clearance intermediate their ends for the adapter, bearings adjustably carried by said jaws for reception of the opposed journals of the adapter, supporting bearings upon the ends of the primary jaw, fixed conical trunnions projecting within said supporting bearings, auxiliary conical bearings mounted intermediate said supporting bearings and trunnions, said auxiliary bearings being movable longitudinally of said supporting bearings, and adjustable connections for maintaining the auxiliary bearings and trunnions against relative displacement.

4. The combination with a generally-circular gun adapter having diametrically opposed journals, of a mount providing universal movement for said adapter, said mount comprising a primary jaw and a secondary jaw arranged for opening and closing movement with respect to the primary jaw, said jaws having their opposed faces disposed in spaced-apart relation to provide a clearance intermediate their ends for the adapter, bearings carried by said jaws for the reception of the opposed journals of the adapter, supporting bearings at the ends of the primary jaw, fixed trunnions projecting within said supporting bearings, an auxiliary bearing interposed between each trunnion and supporting bearing, and means for adjusting each auxiliary bearing within its associated supporting bearing to position the primary jaw relative to said trunnions.

5. The combination with an annular gun adapter having diametrically-opposed journals, of a primary jaw, opposed supporting bearings at the ends of said jaw, fixed trunnions mounted to be received in said supporting bearings, auxiliary bearings between said supporting bearings and said trunnions, threaded means between said supporting bearings and said auxiliary bearings whereby the positions of the auxiliary bearings may be independently adjusted longitudinally within the supporting bearings, a secondary jaw hinged at one end of said primary jaw and disposed in spaced relation intermediate its length to the primary jaw to provide clearance for the adapter, an engaging member carried by said primary jaw to releasably engage the other end of the secondary jaw, opposed adapted bearings, one attached to each of said jaws, for the reception of the journals on said adapter, and means for adjusting said adapter bearings relative to said jaws to position said adapter between said jaws.

6. The combination with an annular gun adapter having diametrically-opposed journals, of a primary jaw, opposed supporting bearings at the ends of said jaw, fixed trunnions mounted to be received in said supporting bearings, auxiliary bearings between said supporting bearings and said trunnions, threaded means between said supporting bearings and said auxiliary bearings whereby the positions of the auxiliary bearings may be adjusted longitudinally within the supporting bearings, a washer within each auxiliary bearing and engaging a stop on said auxiliary bearing and a tie member extending between the adjacent trunnion and the washer for adjustably positioning the washer in engagement with the stop to prevent retrograde movement of the auxiliary bearing, a secondary

jaw hinged at one end to said primary jaw and disposed in spaced relation intermediate its length to the primary jaw to provide clearance for the adapter, an engaging member carried by said primary jaw to releasably engage the other end of the secondary jaw, opposed adapter bearings, one attached to each of said jaws, for the reception of the journals on said adapter, and means for adjusting said adapter bearings relative to said jaws to position said adapter between said jaws for pivotal movement.
